E. PARISI

AUTOMATIC FAN

Filed Sept. 25, 1922

Inventor
Ettore Parisi
By B. Singer, Atty

UNITED STATES PATENT OFFICE.

ETTORE PARISI, OF ROME, ITALY.

AUTOMATIC FAN.

Application filed September 25, 1922. Serial No. 590,458.

To all whom it may concern:

Be it known that I, ETTORE PARISI, manufacturer, a subject of the King of Italy, and residing at Rome, Italy (whose post-office address is No. 7 Via Pianellari, Rome, Italy), have invented certain new and useful Improvements in Automatic Fans, of which the following is a specification.

This invention relates to fans adapted to be operated either by electricity or by means of a suitable clockwork mechanism.

Known fans of this kind comprise a number of fan blades radially arranged around a shaft adapted to be given a rotary oscillating movement by clockwork or other driving means through a chain of spur wheels the last of which is provided with a crank pin and connecting link imparting reciprocating movement to a toothed rack in mesh with a pinion on said shaft.

The fan or the like according to the present invention comprises a suitable mounting or casing in which are mounted two or more fan blades radially arranged and having a to-and-fro movement after the manner of a fan, the movements of one part of them being in a horizontal direction and the movements of the other part being in a vertical direction. By using this device, a slight whirling motion of the air is produced, causing no discomfort but which notwithstanding suffices to refresh the ambient air.

As will hereinafter be seen, the form and outer ornamental design of the fan may be of any suitable or desired type; it should be taken into account that the device in accordance with this invention has not been designed for producing heavy air currents which is the object aimed at in connection with the well known rotary air fans, but is only destined to cause a constant and agreeable motion of the air in all directions, causing no discomfort to the user when coming from a short distance, as for instance, when the fan is placed at the center of the table during eating.

For the better understanding of this description, illustrative detailed drawings have been annexed thereto, wherein:

Figure 1 is a sectional view of a ventilating apparatus constructed in accordance with this invention.

Figure 2 is an upper plan view illustrating the manner of arranging the rods or

links which connect the paddles to the operating device.

In said drawings, 1 indicates a hollow casing of any suitable material, form and outer ornamental design, in the interior of which is conveniently arranged an electric motor 2, or a suitable clock work.

The motor shaft is provided at its end with a worm 3 which operates the worm wheel 4, mounted to rotate on the standard 60 5 and the axle of which is provided with the cranks 6 and 7.

The former of said cranks operates in a vertical direction the forked rod 8 provided at its end with a horizontal slot 9 70 and which by means of suitable links operates the paddles 10 arranged to move on the points 11 and 12, respectively.

The crank 7 operates the rod 13, provided at its end with a vertical slot or opening 14 75 and centered at 15; this rod, by means of its upper forked part operates with its ends the paddles 16, mounted to oscillate in a horizontal direction on the points 17 and 17'.

From an inspection of the drawings it will 80 be readily understood that after starting the motor or driving mechanism, the action of the cranks 6 and 7 in the slots 9 and 14 will cause the movement of the respective rods 8 and 13 which in turn transmit their 85 motion to the paddles 10 and 16.

In the accompanying drawings, a ventilator is shown whose paddles are operated two in a vertical and two in a horizontal direction, but it will be evident that the same 90 means may also be arranged so as to operate the conjoint of the paddles all in the same direction.

The form of construction above described, may be varied by providing an additional wheel, similar to the worm wheel 4, and causing each paddle to be operated by its own connecting rod.

The particular embodiment shown in Figs. 1-4 of the drawings, owing to its proportions, is adapted for use on the table; when it is desired to adopt the apparatus for use near a bed, writing desk, sofa or the like, it may be constructed of greater height, by using extensible leads and telescoping supports, mounted on wheels.

The rod, instead of being operated by means of the slot or slide, may also be acted upon by a simple connecting rod with the necessary links.

The ventilator may consist of two, four or more paddles, of convenient size and the form of the conjoint may be chosen in accordance with the conditions of use.

5 By means of the mechanism above described, the paddles are operated in a manner similar to the movement imparted by a person to a fan and the air current produced thereby, is projected towards the contour 10 of the table, being evenly distributed among the parties occupying the same. A further advantage of the ventilator in accordance with my invention consists in that there is no risk of its paddles becoming detached nor 15 of a person hurting himself on approaching his hand, as is the same case with the centrifugal ventilators of usual construction.

The embodiment shown in Fig. 5 is of the 20 type used for bedsteads, tables, settees or similar articles and has a ventilator for plural uses. In the said figure the standard 1 is adapted to be moved on rolls on the ground and to enclose the driving mechanism. The extension or column of the

standard has fixed thereto by a slideable 25 clamp 20 a plate or table on which books, cups or similar objects may be placed, 10 are the paddles and 18 a shade surrounding a lamp.

Having now described my said invention, 30 I declare that what I claim and desire to secure by Letters Patent, is:—

A fan comprising a stem or casing, a motor therein, including a worm, a gear engaged by said worm, a crank revoluble by 35 said gear, a forked rod mounted for vertical movement and having a slot in which the pin of the crank operates, and fans pivotally mounted on said stems or casing and connected to the forks of said rod for operation thereby.

In testimony whereof I have hereunto signed my name in the presence of two witnesses.

ETTORE PARISI.
